UNITED STATES PATENT OFFICE.

FREDERICK M. ROACH, OF DETROIT, MICHIGAN.

KITCHEN CABINET.

Application filed July 20, 1923. Serial No. 652,794.

To all whom it may concern:

Be it known that I, FREDERICK M. ROACH, a citizen of the United States, a resident of Detroit, county of Wayne, and State of Michigan, have invented an Improvement in Kitchen Cabinets, of which the following description, in connection with the accompanying drawings, is a specification, like characters on the drawings representing like

10 parts.

This invention has reference to cabinets and relates particularly to kitchen cabinets adapted for use in small apartments, although it will be understood that it is susceptible of other uses.

One of the aims of my invention is to provide a combined cabinet and folding table adapted to be secured to the back of a door, such as a closet door for example, 20 so as to swing into the closet to be concealed from view when it is not used. Other advantages will appear in the specification when considered in connection with the accompanying drawings, wherein:

25 Figure 1 is a perspective view of my improved cabinet attached to a door, and

Fig. 2 is a central sectional elevation of the cabinet in closed position and showing the door or table in open position by dotted 30 lines.

Referring to the illustrative embodiment of my invention in the drawings, I have shown a rectangular cabinet 1 of suitable dimensions to fit on the back of a door 2 35 and adapted to be removably secured thereto by suitable fastening means, such as the angle brackets 3 (Fig. 1). A horizontally swinging door or closure 4 is hinged to the front edge of the lower wall of the cabinet, preferably by spring hinges 5.

The inside of the door 4 may be lined or covered with enamelled or plain sheet metal 6 so as to provide a convenient table when it is swung down to a horizontal position as shown in Fig. 2. A pair of swinging legs or supports 7 are preferably pivotally mounted near the upper or free edge of the door (Fig. 2) by hinges 8 and are secured to swing together by a cross brace 45 9.

50 These legs are designed to be folded against the front of the door in its closed position and to swing outwardly therefrom, by gravity, when the door is opened and to rest upon the floor to support it rigidly in 55 a horizontal plane.

The interior of the cabinet is divided into

a plurality of compartments 10, of various sizes, by horizontal partitions 11 and vertical partitions 12 to accommodate dishes and other utensils forming the standard equipment. The two lower horizontal partitions are preferably inclined, as shown in Fig. 2, to prevent the contents of the lower compartments from jarring or falling out upon opening the door.

60 The door may be provided with any suitable locking means, such as the latch 13 on the side wall of the cabinet, cooperating with a screw eye 14 in one edge of the door or closure 4 (see Fig. 1) to hold the door 70 securely in closed position. It will be apparent that other forms of locks or latches may be employed.

In using my improved cabinet, after it is filled with the usual utensils, the closet 75 or other door on which it is suspended is swung open to the desired position, and then the cabinet door 4 is unlatched and swung down to its horizontal position. The legs 7 remain vertical, due to gravity, and 80 support the table without requiring any attention. The weight of the door, when it is in its horizontal position, is sufficient to overcome the strength of the springs in its hinges so that it will remain open. It is 85 then ready for service. The legs, resting upon the floor, will tend to resist movement of the door when the cabinet is being used.

Thus, it will be seen that my disappearing cabinet is not only handy and readily made 90 available for use, but is designed to occupy a minimum of space and has a large storage capacity which constitutes a very important desideratum in connection with modern small apartments, such as a single room 95 apartment wherein disappearing furniture is employed. Further, it may be manufactured at a small cost and is easy to install. Also, because the entire cabinet is supported above the floor, it is not easily accessible to 100 mice and other pests.

Obviously, my invention is not limited to the details of construction herein shown and described but is susceptible of various changes.

105 Having thus described one illustrative embodiment of my invention without restricting myself thereto, what I claim and desire to secure by Letters Patent is:

A cabinet comprising, in combination, a 110 box portion having a plurality of compartments therein, with its back secured to the

inside of a closet or other door, a combined table and closure for said cabinet hingedly mounted on the box portion to swing downwardly approximately to a horizontal position and hinged supporting means mounted adjacent the free end of said closure to rest upon the floor, said supporting means being mounted to swing out-

wardly from the door into supporting position when the door is open and tending to resist swinging movement of the door while the cabinet is in use.

In testimony whereof, I have signed my name to this specification.

FREDERICK M. ROACH.
